(57) **CLAIM**

The ornamental design for a modular wall frame component, as shown and described.

DESCRIPTION

FIG. 1 is a top perspective view of a modular wall frame component showing my new design;

FIG. 2 is a bottom perspective view of the modular wall frame component of FIG. 1;

FIG. 3 is a front elevation view of the modular wall frame component of FIG. 1, with the back elevation view being the same;

FIG. 4 is a right side elevation view of the modular wall frame component of FIG. 1, with the left side elevation view being the same;

FIG. 5 is a top plan view of the modular wall frame component of FIG. 1; and,

FIG. 6 is a bottom plan of the modular wall frame component of FIG. 1.

1 Claim, 4 Drawing Sheets
